CLAIM

The ornamental design for a toilet suspending frame with mirror, as shown and described.

DESCRIPTION

FIG. 1 is a front elevational view of a toilet suspending frame with mirror showing my new design;
FIG. 2 is a rear elevational view thereof;
FIG. 3 is a left side view thereof;
FIG. 4 is a right side view thereof;
FIG. 5 is a top plan view thereof;
FIG. 6 is a bottom plan view thereof; and
FIG. 7 is a perspective view thereof; and,
FIG. 8 shows another embodiment of the present invention, where the mirror has a greater mirror surface.
